(57) **CLAIM**

The ornamental design for a combined mobilephone case and card case, as shown and described.

DESCRIPTION

FIG. 1 is a front and top perspective view of a combined mobilephone case and card case, showing my new design;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view thereof, showing the card case in an unfolded position; and,

FIG. 10 is a perspective view thereof, showing the mobilephone case in an unfolded position.

The broken lines in the figures illustrate portions of the combined mobilephone case and card case that form no part of the claimed design.
